UNITED STATES PATENT OFFICE.

HARRIS KAMRASS, OF NEW YORK, N. Y.

SEAT-ATTACHING DEVICE.

1,276,661.

Specification of Letters Patent. Patented Aug. 20, 1918.

Application filed January 9, 1918. Serial No. 211,038.

To all whom it may concern:

Be it known that I, HARRIS KAMRASS, a citizen of the United States, and a resident of the city of New York, borough of Manhattan, in the county and State of New York, have invented a new and Improved Seat-Attaching Device, of which the following is a full, clear, and exact description.

The invention relates to furniture, and its object is to provide a new and improved attaching device more especially designed for securely and quickly attaching upholstered or plain seats to the seat frame of a chair without the aid of skilled labor. Another object is to enable the owner of a chair to remove a broken or injured seat and replace the same by a new one.

In order to accomplish the desired result, use is made of a series of resilient holding members preferably made of spring wire, and each adapted to bear at one end on the under side of the seat and at the other end on the under side of the seat frame, and connecting members adapted to be held on and depending from the seat and each engaging a corresponding holding member intermediate the ends thereof.

A practical embodiment of the invention is represented in the accompanying drawings forming a part of this specification, in which similar characters of reference indicate corresponding parts in all the views.

Figure 1 is an under side view of a chair provided with the attaching device for holding an upholstered seat to the seat frame;

Fig. 2 is a sectional side elevation of the same on the line 2—2 of Fig. 1;

Fig. 3 is a perspective view of one of the resilient holding members and a link for holding an upholstered seat in position on the seat frame;

Fig. 4 is a perspective view of one of the connecting members used for attaching a plain or a non-upholstered seat to a seat frame in conjunction with a corresponding holding member; and

Fig. 5 is an inverted plan view of a portion of the seat.

The seat attaching device consists of a plurality of resilient holding members 10 and connecting links 11, and each holding member 10 is preferably formed of a piece of spring wire bent to provide a spring coil 12 intermediate its ends. The outer portion 55 of each holding member 10 is provided with an angular arm 13 engaging the under side

of the seat frame 14 of the chair 15 having a detachable seat 16 to be fastened in place by the attaching devices. The arm 13 terminates in a point 17 forced into the under side of the seat frame 14 to hold the holding member against outward or inward movement. The portion 18 of the holding member 10 between the coil 12 and the arm 13 is bent upward adjacent the inner side of 65 the seat frame 14, as plainly indicated in Fig. 2, so as to locate the inner portion of the holding member a short distance from the under side of the seat 16. The holding member 10 terminates at its inner end with 70 an upwardly bent arm 19 which terminates in a horizontal arm 20 resting against the under side of the seat 16.

The link 11 is made in two forms, as plainly shown in Figs. 3 and 4, of which the 75 form illustrated in Fig. 3 is for use on seats 16 which are upholstered, while the form of the link shown in Fig. 4 is for plain wooden seats or pressed unupholstered seats. The link 11 shown in Fig. 3 is in the form 80 of a piece of wire doubled up to provide at its lower end an eye 25 engaging the holding member 10 intermediate the coil 12 and the upwardly extending arm 19. The upper end of the link 11 has its end bent in opposite directions to provide a head 26 adapted to rest on top of the seat 16 underneath the upholstering, the shank of the link extending through keyholes 27 formed in the seat 16. The link shown in Fig. 4 comprises a 90 shank 30 adapted to pass through the keyholes 27 and terminating at its upper end in a head 31 and at its lower end in an eye 32. The head 31 rests on top of the seat 16 and as it is rounded off and made as 95 flat as possible it does not interfere with the occupant of the seat. The eye 32 engages the holding member 10 intermediate the coil 12 and the arm 19, the same as above described relative to the link used on 100 an upholstered seat. It will be noticed that the parts are so proportioned that the spring coil 12 is under tension and consequently the holding members are not liable to shift and securely hold the seat 16 to the seat frame 105 14. As shown in Fig. 1, four attaching devices are used for holding the seat to the frame, but it is evident that two, three or more holding members may be used to accomplish the desired result.

The attaching device shown and described is very simple and durable in construction

and can be cheaply manufactured. The owner of a chair can readily remove a broken or an injured seat and by the use of the attaching device can readily secure an upholstered or other seat to the frame without the use of screws or nails and without producing undesirable projections on the top of the seat.

It will also be noticed that by the use of 10 the keyhole openings 27 the heads 26 and 31 can be passed up through the large end of the keyhole from underneath the seat to engage the shank of the link 11 or 30 with the narrow portion of the keyhole. Thus the 15 upholstery need not be disturbed when placing a link in place on the seat or removing it therefrom.

Having thus described my invention, I 20 claim as new and desire to secure by Letters Patent:—

1. A chair seat attaching device, comprising a plurality of holding members each made of spring wire formed intermediate its ends into a coil, one end of each holding member being adapted to rest on the under side of the chair frame and the other end being adapted to bear on the under side of the seat, and a link adapted to extend through the seat and having a head at its upper end 25 adapted to rest on the upper surface of the seat, the lower end of the link having an engaging means loosely engaging a holding member intermediate its ends.

2. A chair seat attaching device, comprising a plurality of holding members each made of spring wire formed intermediate its ends into a coil, one end of each holding

member having an angular arm adapted to rest on the under side of the chair frame and the other end having an arm adapted to bear 40 on the underside of the seat, and a link having a head at its upper end adapted to rest on the upper surface of the seat, the lower end of the link having an eye engaging a holding member adjacent the said coil. 45

3. A chair seat attaching device, comprising a plurality of holding members adapted to hold a seat in position on the seat frame of a chair, each holding member being formed of a piece of spring wire bent to 50 form a spring coil intermediate its ends, each end having an angular bearing member, of which the outer bearing member is adapted to rest against the under side of the chair frame and terminates in a point adapted to be driven into the chair frame, the inner bearing member resting against the under side of the seat, and links one for each holding member and extending through the 55 seat, each link having a head resting on top of the seat and having an eye engaging the holding member adjacent its coil.

4. A chair seat attaching device, consisting of a piece of spring wire bent to form a coil intermediate of its ends, one end of the 60 wire being bent upwardly and then laterally and the other end being bent downwardly and terminating in an angular and pointed arm, and a link having a head at one end and at the other an eye through which 65 loosely passes the end of the wire which has the upwardly projecting lateral arm. 70

HARRIS KAMRASS.
